UNITED STATES PATENT OFFICE.

HENRY E. MOBLEY, OF TRAFALGAR, INDIANA, ASSIGNOR OF ONE-THIRD TO L. ERT SLACK, OF FRANKLIN, INDIANA, AND ONE-THIRD TO CLAUDE E. RAGSDALE, OF TRAFALGAR, INDIANA.

WRENCH.

No. 878,981.

Specification of Letters Patent.

Patented Feb. 11, 1908.

Application filed February 14, 1907. Serial No. 357,365.

To all whom it may concern:

Be it known that I, HENRY E. MOBLEY, of Trafalgar, county of Johnson, and State of Indiana, have invented a certain new and useful Wrench; and I do hereby declare that the following is a full, clear, and exact description thereof, reference being had to the accompanying drawings, in which like letters refer to like parts.

10 The object of this invention is to provide a simple and improved monkey wrench.

The chief feature of the invention consists in mounting the movable jaw freely slideable upon the shank of the stationary jaw, and 15 having means mounted in connection with the movable jaw adapted, after the movable jaw has been moved up against the nut or the like to be turned into a position to engage threads on the shank of the stationary jaw 20 and thus hold the movable jaw in place. To adjust the wrench for a larger nut, said locking means for the movable jaw is turned so as to disengage the threads on the shank of the stationary jaw, whereby it can be again freely 25 slideable into a new position.

The nature of the invention will be understood from the accompanying drawings and the following description and claims.

In the drawings Figure 1 is a side elevation 30 of the wrench with the movable jaw locked firmly in position for use on a nut. Fig. 2 shows the right-hand half of the wrench with the parts in position to unlock the movable jaw whereby it is slideable freely. Fig. 3 is a 35 plan view of the left-hand portion of Fig. 1. Fig. 4 is a longitudinal section on the line 4—4 of Fig. 2 looking upward. Fig. 5 is a central longitudinal section on the line 5—5 of Fig. 3. Fig. 6 is an end elevation of the adjusting 40 nut showing the mutilated threads therein. Fig. 7 is a section on the line 7—7 of Fig. 1. Fig. 8 is a section on the line 8—8 of Fig. 2, said Figs. 6, 7, and 8 being on a somewhat larger scale than the preceding figures.

45 In detail 10 is what may be termed the fixed jaw, being rigidly secured to its shank 11 which carries a handle 12. The shank 11 is flattened on each side and the top and bottom surfaces are threaded from a point 50 beginning with the handle to a point near the fixed jaw 10. The movable jaw 15 has a hole through it longitudinally, as indicated in Figs. 4, 5, and 8, in which the shank 11 of the wrench fits loosely so that the jaw 15 is 55 slideable on the shank of the fixed jaw 10 into

the desired position with relation to said fixed jaw. It is held in relation with said fixed jaw by means coöperating with the threads on the shank 11.

The movable jaw 15 at its rear end has two 60 threaded rearward extensions 16, one on each side of the shank 11, said extensions having the same width as said shank and being concave transversely so that together with said shank they form a circular threaded body 65 for the locking nut or sleeve 17 that is mounted on them. This nut 17 is milled on the outside so that it can be turned by the thumb and finger, and it is provided with internal mutilated threads 18, that is, it has 70 a series of threads on two opposite sides that extend each about one fourth the distance around the nut, and between said two series of threads at two opposite sides there are no threads whatever. This appears plainly in 75 Fig. 6.

It is obvious from this description of the nut 17 that when it is turned in one position, as for instance in Fig. 6, these threads will, not engage the threads on the shank 11 of the 80 fixed jaw, and then the jaw 15 is readily slideable. But when the nut 17 is turned one fourth of a revolution to the position shown in Fig. 5, the two series of threads 18 therein will engage the threads on the top 85 and bottom surfaces of the shank 11 and thus hold the movable jaw securely against its work.

The nut 17 is held in its two positions by a flat spring 20 fulcrumed on a screw 21 to one 90 side of the movable jaw 15, and at the other end it is reduced to a point that extends for some distance loosely into a hole 22 in the forward side of the nut 17. This hole is so located that when it is turned down to the 95 position shown in Figs. 6 and 7, the movable jaw will be slideable, and when turned up into the position shown in Fig. 8, the nut 17 will lock the jaw 15 in position. The point of the spring 20 fits loosely enough in the hole 22 to 100 permit the oscillatory movement of the spring by the nut to the position shown in Figs. 1 and 2.

What I claim as my invention and desire to secure by Letters Patent is:

105 1. A wrench including a threaded shank with a fixed jaw thereon, a jaw slideable on said shank, a nut mounted in connection with the slideable jaw adapted to engage the threads on said shank for holding the mov- 110

able jaw in the desired position with relation to the fixed jaw and means actuated by the movement of said nut for stopping and holding said nut in position.

- 5 2. A wrench including a shank with mutilated threads thereon, a jaw fixed to said shank, another jaw slidable on said shank, a nut mounted in connection with said movable jaw that is provided internally with 10 mutilated threads to engage the threads on said shank, whereby when said nut is in one position, its threads will engage the threads on the shank and hold the movable jaw fixed, and when in another position of said 15 nut, its threads will not engage the threads of the shank and said jaw will be freely slid- able thereon and means engaged by and actuated by the movement of said nut for stopping and holding said nut in its engaging and 20 disengaging positions.

3. A wrench including a shank with mutilated threads thereon, a jaw fixed to said shank, another jaw slidable on said shank, a nut mounted in connection with said movable jaw that is provided internally with 25 mutilated threads to engage the threads on said shank, whereby when said nut is in one position, its threads will engage the threads on the shank and hold the movable jaw fixed, and in another position of said nut, its threads will not engage the threads of the 30 shank and said jaw will be freely slid- able thereon, and means mounted on said slid-

able jaw and actuated by the movement of said nut for locking said nut in its two posi- 35 tions.

4. A wrench including a shank flattened on two opposite sides and threaded on the top and bottom edges thereof, a jaw fixed to said shank, another jaw slidable on said 40 shank with a rearward threaded extension therefrom on each side of said shank, the threads of said extensions registering with the threads on the shank and complementing each other, a nut mounted on said threaded 45 extensions from the movable jaw that has mutilated internal threads which engage the threads on said shank when the nut is in one position and disengage the threads when the nut is in another position, and a spring ful- crumed at one end to said movable jaw and in engagement at the other end with said nut 50 so as to hold said nut in the positions of engagement and disengagement with the threads of the shank and yet be swung lat- 55 erally by partial rotation of the nut from one locking position to the other, substantially as set forth.

In witness whereof, I have hereunto affixed my signature in the presence of the 60 witnesses herein named.

HENRY E. MOBLEY.
